UNITED STATES PATENT OFFICE

2,435,000

RELAY BEARING STRUCTURE

Oscar S. Field, Rochester, N. Y., assignor to
General Railway Signal Company, Rochester,
N. Y.

Original application October 14, 1940, Serial No.
361,060. Divided and this application August
7, 1944, Serial No. 548,354

9 Claims. (Cl. 175—345)

1

This invention relates to electromagnetic operating means, and more particularly to improved pivoting means for the armatures of electromagnetic relays, and like devices.

This application is a division of my prior application Ser. No. 361,060, filed October 14, 1940, now Patent No. 2,376,534, granted May 22, 1945 and entitled "Light signals for railroads"; and the invention of this application is to be considered in the nature of an improvement over the disclosure of my prior Patent No. 2,360,664, dated October 17, 1944.

In a light signal of the searchlight type as disclosed in the above mentioned parent application, two electromagnetic operating means are provided for operating a movable spectacle to its different positions as well as operating associated contacts to front and back point positions. The armature of each of such electromagnetic operating means is of the tractive type, that is, such armature is pivoted at one end and so associated with the electromagnetic structure as to be pivotally operated between a biased released position and an actuated position. Similarly, various neutral and polarized relays employ armatures of the tractive type, and one of the objects of the present invention is to provide an improved pivoting means for such armatures which will not only be substantially frictionless but which will also show practically no wear although operated over long periods of time.

Another object of the present invention is to provide an improved pivoting means for an armature of an electromagnet which adjustably associates the armature with the pole faces of its electromagnet in such a way that the normal released air gap may be readily adjusted to obtain the desired operating characteristics.

A further object of the present invention is to provide pivoting means which is readily removable for inspection and readily adjustable upon the restoration of the parts in reassembly, or upon the replacement of parts in the event that such replacement might become necessary over a relatively long period of time.

Further objects, purposes and characteristic features of this invention will appear as the description progresses, reference being made to the accompanying drawings, showing in a wholly diagrammatic manner, and in no way whatsoever in a limiting sense one form of the present invention. In the drawings:

Fig. 1 is a sectional view of a light signal spectacle operating mechanism as disclosed in the above mentioned parent application with certain

2

parts removed so as to show the pivot bearing means for the armature constituting one embodiment of the present invention.

Fig. 2 is a sectional side view of one of the electromagnets showing its armature provided with a pivot bearing constituting the embodiment of the present invention, such section being taken on line 2—2 of Fig. 1.

Fig. 3 is an enlarged sectional view of the armature bearing shown in Fig. 1 with the section being taken on line 3—3 as indicated in Fig. 4.

Fig. 4 is an enlarged sectional view of the pivot bearing of the present invention as taken on line 4—4 looking in the direction of the arrows in Fig. 3.

Fig. 5 is a fragmentary sectional view taken on lines 5—5 of Fig. 4.

Referring now to the drawings, the present invention has been disclosed as embodied in a light signal operating mechanism, and in general such mechanism constitutes an outer casing which is constructed to receive the operating mechanism case to thereby provide a proper housing for the mechanism case and to make it possible to replace the mechanism case with a substitute case, if necessary, and yet have the signal properly aligned and focused for its particular signal location. The complete structure of such a signal has not been disclosed herein, since it is believed that the present invention may be understood without a detailed description of such a complete signal structure.

It is believed to be sufficient for the purposes of this description to point out that the signal mechanism includes the operating mechanism case MC shown in Fig. 1 which has a groove 24 on each side to serve as a guide for entering and supporting the mechanism in the outer casing of the signal. This mechanism case MC includes a light projecting unit which has not been shown in detail, and with which a movable spectacle arm 68 is associated. Red, yellow and green roundels R, Y and G respectively are located on the spectacle arm for determining the color of the indication displayed by the signal, and are moved into proper positions by the movable spectacle arm 68 which is carried on a horizontally rockable axle upon which it is operated to its several positions by a suitable operating mechanism connecting it with the armature assemblies Ga and Ya.

The rockable axle for the movable spectacle arm 68 may also have a bearing of the type disclosed herein for the armature assemblies Ya and Ga, but such structure has not been shown herein for the sake of simplicity in the disclosure, such a

structure having been disclosed in detail in the above mentioned parent application Ser. No. 361,060, now Patent No. 2,376,534.

A shelf member 75 is connected to the mechanism casing MC by suitable screws and acts as a support both for the axle of the movable spectacle 68 and for the two operating electromagnets. The two electromagnets are provided with coils 90 and 91, placed side by side and extending from the rear to the front of the mechanism casing. Since these two electromagnets of the signal are identical so far as the mountings for their armatures are concerned, only one of them will be described in detail.

Referring to Fig. 2, it can be seen that a core 92 carries a winding 91, and is positioned above the shelf member 75 by being mounted to the extending legs 93 and 94 of the magnetic structure of the electromagnet, which legs 93 and 94 carry pole shoes 95 and 96 respectively with an air gap between their inner ends. These pole shoes are suitably attached to the shelf member 75, and thus serve as support for the extending legs 93 and 94 and the interconnecting core member 92.

The pole shoes 95 and 96 have the armature assembly Ga associated therewith; and this armature assembly Ga includes the flat plate-like armature 98 which is pivotally supported at the right-hand end and rests against the back stop screw 99 at its left-hand end. Attached to the armature 98 is a residual pin 97 for maintaining a minimum air gap when the armature 98 is in an attracted position. Suitable structure is also connected to the armature 98, as indicated at 144 for transmitting the armature assembly movement to cause the operation of the movable spectacle arm 68.

The pivot bearing at the right-hand end of the armature 98 has been shown in the enlarged views of Figs. 3 and 4; and this pivoted bearing acts to allow the free movement of the armature assembly between the back stop screw 99 and its attracted position as limited by the residual pins 97. For the purposes of the present disclosure, the armature assembly is assumed to be biased to its released position by the action of gravity, but it is to be understood that the armature can be otherwise biased by suitably resilient means.

Referring to Fig. 4, it will be seen that a stud bolt 100 passes through a hole in a clamp plate 101 and an enlarged slot 102 of a U-shaped flat support member 103. This slot 102 in support member 103 can best be seen in Figs. 1 and 3; and these slots, one for each of the stud bolts 100, permit the U-shaped support member 103 to be moved vertically for adjustment of the armature as will presently be described in detail.

The U-shaped support member 103 has two extending legs 104a and 104b which pass through two spaced slots or rectangular holes 107 near the rear edge of the armature 98. The armature 98 is also provided with a V-shaped slot 109 in the top surface of the armature and along its rear edge in line with the two spaced rectangular slots 107, as best seen in the fragmentary view of Fig. 5.

In assembling the armature on its pivot bearing, an upper bearing plate 105 having slotted ends 106, is first passed between the two legs 104a and 104b and against the cross portion of the support member 103. Assuming that the support member 103 is held in position by a rough adjustment, then the armature 98 is moved into position with the legs 104a and 104b passing through their respective slots 107. A cylindrical

rod-like or needle bearing member 108 is placed in position in the V-slot 109, and then the armature is moved so that such needle bearing 108 is pressed against the bearing plate 105.

Coil spring members 110 are placed over their respective legs 104a and 104b and are held in position by cup-shaped stops 111. Each stop 111 is pressed against the lower portion of its respective spring by shoulders 112 of the head of a U-shaped clip 114 fastened at its lower end by a bolt 113.

Referring to Figs. 3 and 4, it will be seen that the lower face of the armature is provided with recesses beneath each slot 107 for the respective legs 104a and 104b, which recesses provide holding means for the upper ends of their respective spring members 110. Each U-shaped clip member 114 extends upwardly so that its legs terminate just short of the lower face of such recess, and thus provide a limit against which the armature 98 can abut to prevent its being pulled downwardly against the spring tension. This limited distance of movement for the armature 98 is not sufficient to allow the removal of the needle bearing 108 out of its V-shaped notch in the upper face of the armature. In other words, the clips 114 must be removed if the bearing rod 108 is to be lifted out of its V-shaped notch or groove in the armature.

Referring to Fig. 3, it will be seen that the legs 104a and 104b of the support member 103 provide a stop against which the endwise motion of the needle bearing 108 is limited, since the slots through which the respective legs pass are in line with the V-shaped slot containing the needle bearing (see Fig. 5).

With the pivot bearing thus assembled, the armature 98 can then be brought into proper positions, that is, the air gap at the right-hand end of the armature as seen in Fig. 2 may be made larger or smaller to obtain the desired operating characteristics. All that is necessary to obtain the adjustment is to loosen the stud bolts 100 and move the support member 103 to the desired position, and then tighten the bolts 100 to hold the bearing in such adjusted position.

It should be noted that the U-shaped member 103 and the clip members 114 are preferably formed of some suitable non-magnetic material although this is not entirely necessary to obtain the proper operation of the electromagnetic structure, but facilitates in maintaining a minimum amount of leakage of the magnetic flux of the structure. The upper bearing surface member 105 is preferably formed of some hardened material which is very durable and which has a very smooth surface against which the needle member 108 may bear. The needle bearing member 108 is also preferably formed of some suitably hardened material, which will be very durable, and which will provide a minimum of wear with respect to the bearing member 105.

As viewed in Fig. 4, it will be seen that the needle bearing member 108 has a diameter of such a value with respect to the depth of the V slot in the armature, that the upper surface of the needle member 108 extends a slight distance above the surface of the armature. This distance need be relatively small, since the movement of the armature is relatively slight when considered in the number of degrees moved on its pivot point. It can also be seen that the diameter of the needle member 108 may be selected to cooperate with the V slot, and yet any desired air gap between the armature and the

pole pieces may be obtained by the construction and adjustment of the support member 103.

Since the bearing member 106 contacts the V slot on two surface lines, and only contacts the bearing member 105 on one surface line, any movement of the armature will cause a rocking motion of the needle bearing member 108 with respect to the upper bearing surface 105, and in this way a minimum amount of friction is produced. This organization of bearing means furnishes a very simple and durable bearing which is practically frictionless, and which has a very long life although subjected to severe operating conditions.

The operation of an electromagnet having an armature with a bearing constructed in accordance with the present invention, is very simple and reliable. It will be readily apparent that the energization of the winding 31 (see Fig. 2) will produce of a magnetic flux in the magnetic circuit of the structure which will produce lines of force in the air gap between the pole shoes and the armature 98, which lines of force tend to attract the armature away from the back stop screw 99 toward the pole shoes 95 and 96 in order to reduce the reluctance of the magnetic circuit in the usual way for tractive type relays. The movement of the armature 98 toward the pole shoes 95 and 96 is limited by the residual pins 81 and the bearing adjustment at the right-hand end. It may be desirable to vary the air gap of the armature so as to obtain the desired operating values. This may be done in either of two ways, namely, by the adjustment of the back stop screw 99, or by changing the adjustment of the bearing member. Changing the back stop screw 99, of course changes the amplitude of the movement of the armature; while the changing of the air gap by the adjustment of the bearing, does not materially affect the amplitude of the armature movement. With these two adjustments, the extent of the armature movement and its operating characteristics may be readily adjusted to suit the requirements of practice.

Having thus shown one form of a bearing for tractive type armatures and the like, as one specific embodiment of the present invention, it is to be understood that such embodiment is shown solely by way of example and is not intended in any manner whatsoever in a limiting sense. It is to be understood that various modifications, adaptations and alterations can be applied to the embodiment of the present invention to meet the requirements of practice without in any manner departing from the spirit or scope of the invention except as limited by the appended claims.

Having thus described my invention I now claim:

1. In an electromagnetic relay structure, an armature, a pivot means for the armature, including, an open transverse groove in the upper face of the armature, a needle-like bearing resting loosely in the groove and projecting above the surface of the armature, a hole extending through the armature at each end of the groove, a U-shaped holder having its legs extending downward through the holes, an upper bearing plate slidable on the legs and positioned between the needle bearing and the head of the U, a spring stop at the free end of each leg, a compression spring on each leg between the stop and the lower face of the armature, armature operating means, and means adjustably mounting the U-shaped holder on the operating means.

2. In an electromagnetic relay structure, an armature, a pivot means for the armature, including an open transverse groove in the upper face of the armature, a needle-like bearing loosely resting in the groove and projecting above the surface of the armature, a hole extending through the armature near each end of the groove, a U-shaped holder having its legs extending downward through the holes, an upper flat bearing plate slidable on the legs and positioned between the needle bearing and the head of the U, a spring stop at the end of each leg, a compression spring on each leg and bearing against the stop and the lower face of the armature, an armature operating means, and means adjustably holding the U-shaped holder to the operating means, the legs of the U-shaped holder being positioned on the axis of the needle bearing to prevent the needle from sliding out of its groove by endwise movement.

3. In an electromagnetic relay structure, an armature, a pivot means for the armature including an open longitudinal groove in the upper face of the armature, a needle-like bearing loosely resting in the groove and projecting above the surface of the armature, a hole extending through the armature near each end of the groove, a U-shaped holder having its legs extending downward through the holes, an upper bearing plate notched for slidable reception between and on the legs and positioned between the needle bearing and the head of the U, a spring stop at the free end of each leg, a compression spring on each leg between the stop and the lower face of the armature, means adjustably holding the U-shaped holder to a fixed support, and a stop arm on each spring stop extending toward the armature and terminating just short of the armature, whereby to prevent moving the armature against the spring tension far enough to allow the needle bearing to be removed from its groove by sidewise movement.

4. In an electromagnetic relay structure, an armature, a pivot means for the armature, including an open V-shaped groove in the upper face of the armature, a needle-like bearing loosely resting in the groove and projecting above the surface of the armature, a hole extending through the armature near each end of the groove, a U-shaped holder having its legs extending downward through the holes, an upper bearing plate, notches in the bearing plate for sliding the plate upon and between the legs to be positioned between the top of the needle bearing and the head of the U, a spring stop at the end of each leg, a compression spring on each leg between the stop and the lower face of the armature, a support means adjustably holding the U-shaped holder to the support, the legs of the U-shaped holder being positioned on the axis of the needle to prevent the needle from sliding out of its groove by endwise movement, and a stop arm on each spring stop extending toward the armature and terminating near enough to the armature to prevent movement of the armature on the legs and against the spring tension sufficient to allow the needle bearing to be removed from its groove by lateral movement.

5. In a needle type bearing for pivotally mounting a movable flat-like member with respect to a fixed support, an elongated groove in one surface of said movable member, a plane hardened surface bearing member adjustably mounted to said support, a cylindrical rod bearing loosely received

in said groove and having a diameter such that its outer surface projects above the surface of said movable member, two legs projecting from said adjustably mounted bearing member and respectively passing through a hole at each end of said groove to limit the lateral movement of said movable member and to provide an abutment at each end of the groove for the full diameter of said cylindrical rod to prevent more than limited endwise movement of said cylindrical rod, and spring biasing means mounted on each of said leg members to cause said movable member to press said cylindrical rod against said bearing member.

6. In an electromagnetic relay structure, an electromagnet having extending pole faces, a flat plane-like armature associated with said pole faces, a support member having an elongated hardened plane surface, means adjustably mounting said support member with respect to said electromagnet pole faces, a bearing between said armature and said support member comprising, an elongated groove in one face of said armature extending along its pivotal axis, a hardened cylindrical rod loosely received in said groove and having a diameter sufficient to bring its surface outside of the surface of said armature, means limiting endwise movement of said rod, and spring means acting adjacent each end of said groove and in line therewith for pressing said armature toward said support member to provide for a rocking motion of the armature with respect to said pole faces by a rolling contact of said rod on the hardened plane surface of said support member, whereby said armature can have the air gap between it and said pole faces adjustably determined without materially changing the extent of armature movement.

7. In a needle type bearing for pivotally mounting a movable flat-like member with respect to a fixed support, a V-shaped elongated groove in one surface of said movable member, a hardened plane bearing surface member adjustably mounted to said support, a hardened cylindrical rod loosely received in said groove and having a diameter sufficient to bring its surface outside of the surface of said movable member, two legs projecting from said adjustably mounted bearing and passing through holes at each end of said groove to thereby provide only limited amount of lateral movement of said movable member and at the same time to prevent endwise movement of said cylindrical rod, spring biasing means on each leg member for acting when compressed to cause said movable member to press said cylindrical rod against said bearing surface member, and a removable stop means mounted on each leg for compressing its respective spring means and also acting to prevent movement of said movable member longitudinally of said leg members against the compression of said springs, whereby said cylindrical rod bearing can be removed only upon the demounting of said removable stop means.

8. In an electromagnetic relay structure, a flat plane-like armature adapted to cooperate with the electromagnet of the relay structure, a support member having two extending leg portions,

means adjustably mounting said support member with respect to the electromagnet, a bearing between said armature and the support member comprising, a hardened plane surface bearing member held between the legs of said support member, an elongated groove in the armature on that side facing said support member, a hardened cylindrical rod loosely located in said groove and having a diameter such that its surface is raised above the surface of said armature, said armature having two receiving holes at the ends of said groove and in line therewith and mounted on said support member with said extending legs passing through said holes to thereby prevent endwise movement of said cylindrical rod and to also allow only a limited lateral movement of said armature, compression spring means on each of said extending legs for causing said armature to press the surface of said rod against said bearing member, and a removable stop means mounted on each leg for limiting the movement of said armature longitudinally of said legs against the compression of said springs to thereby prevent the displacement of said cylindrical rod out of said groove without first demounting said removable stop means.

9. In an electromagnetic relay structure, a flat armature adapted to cooperate with the electromagnet of the relay structure, a flat-like support member having two extending leg portions, means adjustably mounting said support member with respect to the electromagnet, a bearing between said armature and the support member comprising, a hardened flat-like bearing member slotted at each end so as to fit between the legs of said support member with said legs being received by said slots, a V-shaped groove extending across the armature on that side facing said support member, two receiving holes in said armature near the ends of said groove and in line therewith so that said armature can be mounted on said support member with said extending legs passing through said holes, a hardened cylindrical rod loosely located in said groove between said holes and having a diameter such that its surface is raised above the surface of said armature, whereby endwise movement of said cylindrical rod is prevented by said extending legs, compression spring means on each of said extending legs for causing said armature to press the surface of said rod against said bearing member, and a removable stop means mounted on each leg for limiting the movement of said armature longitudinally of said legs against the compression of said springs to thereby prevent the displacement of said cylindrical rod out of said groove.
